UNITED STATES PATENT OFFICE

SAMUEL DWORKIN, OF PASSAIC, NEW JERSEY, ASSIGNOR TO PASSAIC KIDDY SHOP, INC.,
A CORPORATION OF NEW JERSEY

GARMENT HANGER

Application filed January 20, 1932. Serial No. 587,824.

The present invention relates to a garment hanger and has for its prime object to provide a combination hanger for children's panty dresses, suits, coats, trousers and the like and has for its principal object the provision of means on the body of the hanger for supporting trousers or the like, said means being foldable to a compact position in relation to the body when not in use.

Another object of the invention resides in the provision of a combination garment hanger of this nature which is exceedingly simple in its construction, inexpensive to manufacture, strong and durable, easy to manipulate, thoroughly efficient and reliable in use and otherwise well adapted for the purpose for which it is designed.

With the above and other objects in view as will appear as the description proceeds, the invention resides in certain novel features of construction, and in the combination and arrangement of parts as will be herein-after more fully described and claimed.

In the drawing:—

Figure 1 is an elevation of the hanger showing the auxiliary means in an operative position, and showing a portion of the body in section.

Figure 2 is a similar view showing the auxiliary means in folded position.

Figure 3 is a transverse section taken substantially on the line 3—3 of Figure 1.

Referring to the drawing in detail it will be seen that the numeral 5 denotes a substantially arcuate elongated body from which rises a hook 6 or other means whereby the body may be hung up in the usual manner. Depending from the center of the body 5 is a substantially U-shaped loop 7. Recesses 8 are formed in the under edge of the body 5 equidistant from the center thereof and equidistant from the ends thereof. Across these recesses are pins 9. Rods 10 are provided at their upper ends with offset eyes 11 circumjacent the pins 9 and rockable thereon. Clips or other suitable fastening means 12 are mounted on the free ends of the rods. When the rods are depending downwardly from the body 5 as shown in Figure 1 the fastening elements or clips may be engaged with

a garment such as trousers or the like for supporting the same from the hanger. When the rods 10 and their clips 12 are not in use they may be swung up to the position shown in Figure 2 and the clips engaged with the loop 7.

It is thought that the construction, manipulation and advantages of this invention will now be readily understood by those skilled in this art without any further detailed description. The present embodiment of the invention has been described in considerable detail because in actual practice it attains the features of advantages enumerated as desirable in the statement of the invention and the above description.

It will be apparent that changes in the details of construction may be resorted to without departing from the spirit or scope of the invention as hereinafter claimed or sacrificing any of its advantages.

Having thus described my invention, what I claim as new is:—

1. A garment hanger of the class described including, in combination, a body, rods swingably mounted on the body, fastening elements on the free ends of the rods, a loop on the body between the rods with which the fastening elements may be engaged.

2. A garment hanger of the class described including a body, rods swingably mounted on the body, fastening elements on the rods, and means on the body with which the fastening elements may be engaged to hold the rods in a folded position adjacent the body.

3. A garment hanger of the class described including a body, the under edge of the body being formed with recesses, pins across the recesses, rods having ends formed with eyes circumjacent the pins and rockable thereon within the recess, fastening elements on the free ends of the rods, and a loop extending from the body between the recesses with which the elements may be engaged.

In testimony whereof, I affix my signature.

SAMUEL DWORKIN.
